The ornamental design for a gel-like fragrant material with a pearl-like appearance, as shown and described.

DESCRIPTION

FIG. 1 is a perspective view of a gel-like fragrant material

with a pearl-like appearance showing our new design, shown in a form of an intended use;

FIG. 2 is a side elevational view of the gel-like fragrant material with a pearl-like appearance shown in FIG. 1.

FIG. 3 is a top plan view of the gel-like fragrant material with a pearl-like appearance shown in FIG. 1.

FIG. 4 is a bottom plan view of the gel-like fragrant material shown in FIG. 1.

FIG. 5 is a perspective view of a gel-like fragrant material with a pearl-like appearance showing our new design, shown in another form of an intended use;

FIG. 6 is a side elevational view of the gel-like fragrant material shown in FIG. 5.

FIG. 7 is a top plan view of the gel-like fragrant material shown in FIG. 5.

FIG. 8 is a bottom plan view of the gel-like fragrant material shown in FIG. 5.

FIG. 9 is a perspective view of a gel-like fragrant material with a pearl-like appearance showing our new design, shown in another form of an intended use;

FIG. 10 is a top plane view of the gel-like fragrant material shown in FIG. 9.

FIG. 11 is a left-side view of the gel-like fragrant material shown in FIG. 9.

FIG. 12 is a back view of the gel-like fragrant material shown in FIG. 9.

FIG. 13 is a right-side view of the gel-like fragrant material shown in FIG. 9; and,

FIG. 14 is a bottom plan view of the gel-like fragrant material shown in FIG. 9.

The broken-like showing of environmental structure in FIGS. 1-14 is for illustrative purposes only and forms no part of the claimed design.

The characteristic feature of the design resides in its pearl-like appearance.
